Inventor.

Henry R. Holdeman

UNITED STATES PATENT OFFICE.

HARRY R. HOLDEMAN, OF LOS ANGELES, CALIFORNIA, ASSIGNOR TO THE J. M. FELDMAN CO. INC., OF LOS ANGELES, CALIFORNIA.

DESIGN FOR AN ITALIAN-EFFECT LIGHTING-FIXTURE BANDING.

Application filed November 21, 1927. Serial No. 24,227. Term of patent 3½ years.

To all whom it may concern:

Be it known that I, **HARRY R. HOLDEMAN**, a citizen of the United States, residing at Los Angeles, in the county of Los Angeles and State of California, have invented a new, original, and ornamental Design for an Italian Effect Lighting-Fixture Banding, of which the following is a specification, ref-

erence being had to the accompanying drawing, forming part thereof.

The figure is an elevational view of a section of the banding showing my new design.

I claim:

The ornamental design for an Italian effect lighting fixture banding as shown.

HARRY R. HOLDEMAN.
